UNITED STATES PATENT OFFICE.

WARREN BOLEY, OF LODI, OHIO.

CABLE HANGER.

Application filed July 3, 1922. Serial No. 572,463.

To all whom it may concern:

Be it known that I, WARREN BOLEY, a citizen of the United States, residing at Lodi, in the county of Medina and State of Ohio, have invented certain new and useful Improvements in Cable Hangers, of which the following is a specification.

My invention relates to improvements in cable hangers, and more particularly to that 10 class or type employed for suspending electric cables from supporting or "messenger wires."

My invention relates more particularly to what may be termed a "double or two-part" 15 cable hanger of the class mentioned, being made up of main and secondary cable receiving and supporting loops adapted to be independently and detachably connected to or detached from each other for carrying or 20 supporting a plurality of cables or service wires from a single "messenger wire."

The primary object of the invention is to provide a generally improved cable hanger of the type or class indicated which will be 25 exceedingly simple in construction, cheap of manufacture and efficient in use.

A further object is the provision of an improved attachment in the specific form of a second hanger or auxiliary cable receiving 30 and supporting loop adapted to be readily attached to or detached from any ordinary or conventional form of cable hanger.

With the above mentioned and other ends in view, the invention consists in the novel 35 construction, arrangement and combination of parts, hereinafter described, illustrated in one of its embodiments in the accompanying drawings and particularly pointed out in the appended claims.

40 Referring to the drawings, forming a part of this specification, Figure 1 is an edge or end elevation of a cable hanger, constructed in accordance with this invention, the messenger wire and supported cables being 45 shown in cross section and in dotted lines, respectively.

Fig. 2, a side elevation of the same.

Fig. 3, a fragmentary cross sectional view taken on line 3—3 of Fig. 1.

50 Similar numerals of reference designate like parts throughout all the figures of the drawings.

The main cable hanger embodying the usual cable receiving and supporting loop 55 1, for supporting the overhead cable 2, may be of any suitable or conventional form, the

loop 1, in the present instance, terminating in hooks 1^a, adapted to take over the usual messenger wire 3. In the present instance the main body portion or loop 1 is formed of flat stock bent to form an exterior channel shaped portion 1^b thereby forming a rounded or beaded interior for receiving and carrying the cable 2.

The second or auxiliary hanger comprises 60 a second or auxiliary cable receiving loop 4, adapted to extend below the plane of the first loop 1 and provided with attaching arms 4^a, adapted to be readily attached to or detached from the main cable hanger 1.

The second or auxiliary hanger is preferably made up of a single length of spring wire bent upon itself to form the loop or main body portion 4, the ends of the loop 4 crossing each other and terminating in 75 curved or loop shaped arms 4^a, conforming substantially to the exterior conformation or contour of the main cable suspending loop 1, the ends of the arms 4^a terminating, in the present instance, in projections 4^b, ex-

70 tends inwardly, said projections 4^b, in the present instance, being in the specific form of short hooks adapted to enter into openings 1^c, the latter being preferably arranged near the top or upper portions of the main loop 1. The purpose of the second hanger, or of the supplementary attachment consisting of the parts 4 and 4^a, is to provide a second loop to receive and carry a second cable 5 or a plurality of service wires, or 80 the like, or such second cable and one or more service wires may be conveniently carried therein, and it will be apparent that the cables or wires carried in the loop 4 may be readily detached on occasion by detach-

85 ing the arms 4^a, thereby withdrawing the projections or hooks 4^b from the openings 1^c, and in order to provide for the convenient attachment of the second hanger or loop, the conventional form of loop 1 may be provided when originally manufactured with such openings 1^c to later receive the second hanger or loop when the particular demands 90 render the same necessary or desirable in suspending additional cables or service wires from a single messenger wire 3.

95 From the foregoing description, taken in connection with the accompanying drawings, the operation and advantages of my invention will be readily understood.

100 Having thus described one of the embodiments of my invention, without having at-

tempted to set forth all the forms in which it may be made, or all the modes of its use, what I claim and desire to secure by Letters Patent, is—

- 5 1. A cable hanger, comprising a cable hanger loop, and a second hanger loop having similarly shaped spring loop arms surrounding and detachably connected therewith.
- 10 2. A cable hanger, comprising main and auxiliary hangers, said auxiliary hanger comprising a cable receiving loop and an open attaching loop of similar form surrounding and engaging said main loop.
- 15 3. A main hanger loop, and a second cable hanger comprising a single length of wire bent into loop form and terminating in spring cross arms and projections forming an open attaching loop to surround and engage with the main hanger loop.
- 20 4. In a cable hanger, including a main cable loop, an attachment comprising a cable receiving loop terminating in cross arms forming a split attaching loop curved to conform to and engage with said main cable loop.
- 25 5. In combination with a main loop a cable hanger attachment, comprising a single length of wire bent into loop form and terminating in spring cross arms having hooks forming an open attaching loop to extend about and engage with the main loop, respectively.

6. In a cable hanger, including a main hanger loop, a hanger attachment comprising a cable receiving loop terminating in loop shaped arms having projections adapted to surround and engage, respectively, with the main hanger loop.

7. In a cable hanger, a hanger attachment comprising a single length of wire bent into a cable receiving loop and having curved segmental shaped arms terminating in projections adapted to surround and engage, respectively, with a main hanger loop.

8. A cable hanger, comprising main and auxiliary hanger loops, said main loop having an exterior channel portion provided with openings, and said auxiliary hanger loop terminating in cross arms curved to conform to the exterior of said main loop and terminating in projections seated in said openings.

9. A cable hanger made up of main and secondary loops, said main loop having a channel on its exterior and provided at its top with recesses, and said secondary loop comprising a single length of wire bent midway of its ends forming a spring loop having its sides terminating in loop shaped arms seated in the channel portions of said main loop and terminating in projections seated in said recesses.

In testimony whereof I have affixed my signature.

WARREN BOLEY,
